UNITED STATES PATENT OFFICE.

FRANK J. VIERLING AND CLOVER G. IRVINE, OF MINNEAPOLIS, MINNESOTA; SAID VIERLING ASSIGNOR TO SAID IRVINE.

PENCIL.

Application filed December 6, 1926. Serial No. 152,867.

Our invention relates to a pencil of the type disclosed and broadly claimed in the Frank J. Vierling application filed June 3, 1926 under Serial Number 113,450, and has 5 for its object to provide such a pencil with means by which its lead may be given a coarse quick predetermined step by step axial adjustment or a micrometric screw adjustment.

10 To the above end, the invention consists of the novel devices and combinations of devices hereinafter described and defined in the claims.

15 In the accompanying drawings, which illustrate the invention, like characters indicate like parts throughout the several views.

Referring to the drawings:

Fig. 1 is a view of the improved pencil principally in longitudinal central section;

20 Fig. 2 is an elevation of the inner casing member removed from the outer casing member and showing by means of broken lines, one of the spare leads partly removed from the lead holder;

25 Fig. 3 is a fragmentary detail view, with some parts sectioned, of the outer casing member;

Fig. 4 is a transverse section taken on the line 4—4 of Fig. 2; and

30 Fig. 5 is a fragmentary view, with some parts sectioned, showing a slight modification of the lead holder and ejector.

Referring first to the invention shown in Figs. 1 to 4 inclusive, the improved pencil 35 comprises a casing made up of inner and outer telescopically connected tubular members 6 and 7, respectively, and a lead-feeding stem 8 having a sleeve-like lead holder and ejector 9 slidable thereon. The lower 40 end of the casing member 7 is contracted to afford a point 10 having an opening through which a lead α held by the holder 9 may be fed and guided for endwise movement in either direction.

45 An eraser 11 is mounted in a seat 12 formed in the upper end of the inner casing member 6 by circumferentially expanding the same. A long screw thread 13 is formed in the inner end portion of the inner casing mem-

ber 6 by pressing the same therefrom, and a short nut-acting screw thread or element 14 is formed in the outer casing member 7 by pressing the same therefrom, for co-operation with the screw thread 13 to adjustably 50 connect the two casing members.

The casing members 6 is longitudinally slit at 15 from its inner end portion completely through the screw thread 12 and it is also circumferentially slit at 16 on each side of the slit 15. The purpose of slitting the casing member 6 at 15 and 16 is to permit the same to yieldingly contract and expand when axial pressure is applied to the casing members 6 and 7 in reverse directions and thereby cause the screw threads 13 and 14 to ride 60 over each other with a ratchet-like action.

Said lead-feeding stem 8 is secured to the casing member 6 by having its upper end portion bent to form a spirally wound section 17 that encircles said stem. This spirally wound section 17 of the stem 8 is forced into said inner casing member under sufficient pressure to slightly contract said section 17 so as to yieldingly engage said casing member just below the seat 12 under spring action of sufficient tension to positively secure said stem to the inner casing member 6 for common movement therewith. The spiral section 17 holds the respective end portion of the stem 8 axially aligned with the casing member 6, 80 and it also holds said stem against endwise movement in respect to said member for common axial and turning adjustment therewith.

The lead holder 9 is limited in its projecting movement on the stem 8 below the lower end thereof by a pair of diagrammatically opposite lugs 8' formed on said stem, and projecting into longitudinal slits 18 in the lower end portion of said lead holder. The internal diameter of the lead holder 9 at 90 the slit 18 is such that the same is slightly expanded when the lead α is forced therein to frictionally hold the same in the lead holder 9. The retracting movement of the lead holder 9 on the stem 8 is limited by 95 a stop 19 on the stem 8 formed by flattening said stem. Said stop 19 is so located on the stem 8 that the lead holder 9 can be retracted into a position in which said stem projects completely therethrough. By thus mounting 100 the lead holder 9, the lead α may be ejected from said holder by sliding said holder upward on the stem 8 until engaged by the stop 19.

Formed on the upper end of the lead holder 9 is a cup 20 which has sliding engagement with the inner surface of the outer casing 7 and holds the respective portion of the stem 8 axially positioned in said casing member.

The inner casing member 6 affords a com-

partment for spare leads *y* and the cup 20 affords a bottom member for holding said leads, and is axially spaced from said member to afford a passage for said leads when filling said compartment therewith, or removing one of the leads therefrom to be placed in the lead holder 9.

Obviously, the spiral section 17 and the cup 20 holds the stem 8 axially positioned in the casings 6-7 with the lead holder 9 axially aligned with the lead opening in the casing point 10 and against lateral movement. With the lead holder 9 thus positioned the lead *x* is held thereby for straight line adjusting movement through the point 10. Said lead *x* is firmly held by the lead holder 9 and the point 10 during writing action and prevents said lead from breaking.

Spare leads *y* are inserted into the compartment 21 or removed therefrom, as one thereof is indicated by broken lines in Fig. 2, when the casing member 6 is removed from the casing member 7. The lower ends of the spare leads *y* rest in the cup 20 and are thus held in the compartment 21 when the casing members 6 and 7 are separated.

A spring clip 22 is attached to the casing member 6 just below the seat 9 by bending the upper end portion of said clip inward and then upon itself to afford a flat prong 23 which is inserted into said casing through an aperture therein before the spiral section 17 is inserted into said casing. After the prong 23 is in position in the casing member 6 the spiral section 17 of the lead-feeding stem 8 is inserted into said casing, and presses the prong 23 against the inner wall of said casing and rigidly holds the same as shown in Fig. 1.

40 A coarse quick predetermined step by step axial adjustment may be given to the lead *x* by applying slight axial pressure to both casing members 6 and 7 in opposite directions to cause the threads 13 and 14 to ride over each other with a ratchet-like action under the circumferential yielding movement of the casing member 6 which is permitted by the slit 15. The slits 16 permit free contracting movement of the casing member 6 at the inner end of the slit 15. The casing members 6 and 7 may be separated or telescoped, the one within the other, by this same relative movement of said casing members. Or a micrometric screw adjustment may be given to the lead *x* by the relative rotation of the casing members 6 and 7 under the action of the screw threads 13 and 14 turning the one with in the other.

After the lead *x* is too short for further

use the casing members 6 and 7 are separated 60 and said lead ejected by giving the lead holder 9 a retracting movement on the stem 8 to project said stem therethrough and force the lead *x* out of the lead holder 9.

Referring now to the invention shown in Fig. 5 the lead feeding stem 24 is provided with a single radially projecting lug 25 which extends into a slit 26 formed in the lead holder 27 on which is formed a lead-holding cup 28. The structure shown in this figure 70 is the same as that shown in Figs. 1 and 2 with the exception that the lead-feeding stem 24 is provided with only a single lug.

What we claim is:

1. A pencil comprising an outer barrel and 75 a shell formed of resilient material and open at its inner end and telescopically slideable within said barrel but having one end extending out of said barrel, interengaging means carried by the barrel and the shell whereby 80 to cause advance or retraction of the shell under relative rotative movement, the inner portion of said shell being provided with a longitudinal slot which leads into the open end of said shell, the other end of said slot 85 terminating in a transversely extending slit formed in the body of the shell.

2. An automatic telescopic pencil, including an inner member comprising a shell 90 formed of resilient metal and open at its inner end, a lead carrier resiliently mounted within said member and extending longitudinally of said shell and beyond said open end, the inner portion of said shell being provided with a longitudinal slot leading into said open end 95 of the shell and terminating at the other end in a cross slot formed in the body of the shell, and the other end of said shell extending beyond the end of said barrel to form a substantial portion of the body of the pencil and 100 provide gripping means for rotating the shell with respect to the barrel.

3. A pencil comprising an outer barrel having a spiral bead extending around the inside thereof, a shell telescopically slideable 105 within said barrel, said shell being longitudinally split adjacent one end and provided with spiral ridges thereon adapted to resiliently engage the bead on the inside of the barrel, and having the other end extending out of said barrel, the said outer end providing means whereby the barrel and the shell may be given a relative endwise movement or 110 may be relatively rotated.

In testimony whereof we affix our signatures.

FRANK J. VIERLING.
CLOVER G. IRVINE.
